UNITED STATES PATENT OFFICE.

WALTER H. STEWART, OF FRANKLIN, NEW HAMPSHIRE.

THICKENING-THREAD-FEED MECHANISM FOR KNITTING-MACHINES.

SPECIFICATION forming part of Letters Patent No. 451,703, dated May 5, 1891.

Application filed January 6, 1890. Serial No. 336,062. (No model.)

To all whom it may concern:

Be it known that I, WALTER H. STEWART, of Franklin, in the county of Merrimac and State of New Hampshire, have invented certain new and useful Improvements in Thickening-Thread-Fee Mechanism for Knitting-Machines, of which the following is a specification.

My invention has reference to circular knitting machines generally, and particularly to that class of machines in which the needles are radially arranged and are reciprocated in the groove of a needle-bed toward and from a common center by means of cams or inclines on a rotating cam-plate.

It is the object of my invention to provide an improvement on machines of the class mentioned, whereby an extra or thickening yarn may be introduced to the needles to thicken or strengthen the fabric at any desired point—as, for example, the heel and toe portions of stockings.

The invention consists in providing an extra yarn-guide adapted to be thrown into and out of operation, connecting the said yarn-guide and its supporting means with the cam-plate, and constructing and arranging means whereby the said yard-guide may be automatically moved and controlled, all as is hereinafter more fully and particularly set forth, reference being had to the accompanying drawings, and to the letters and signs of reference marked thereon, forming a part of this specification, the said letters and signs designating the same parts or features, as the case may be, wherever they occur.

Of the said drawings, Figure 1 is a top view of a knitting-machine adapted to have my improvements applied thereto, both the usual and my improved extra yarn-feeding devices being removed therefrom. Fig. 2 is a sectional view of the cam-plate and needle-bed shown in Fig. 1 and enough of the immediate connections of the said parts to explain the nature of my improvements, and showing also a side view of my invention. Fig. 3 is a top view of my improvement separated from the machine. Fig. 4 is a top view of the bracket attached to the cam-plate, which supports the extra yarn-carrier and part of its operating means.

In the drawings, *a* designates the needle-bed provided with radial grooves, in which are arranged the needles *b*, adapted to be reciprocated in the said grooves by means of cams or inclines *c*, connected with the cam-plate *d*, which latter device is constructed to be rotated by means of a bevel-pinion *e*, secured to the driving-shaft *f*, on which the driven loose pulleys *g* are arranged, and between which pulleys is arranged the sliding clutch member *h*, splined on shaft *f*, so as to turn the same when the clutch member is connected with either of the pulleys *g*.

i j are levers connected with the arbor *k* and adapted to be operated by a pin *l* to effect a reciprocation of the cam-plate *d*.

m n are levers adapted to be actuated by pins on the cam-plate for operating mechanism, whereby the needles are thrown into and out of operation in the knitting of heel and toe work.

o is a ratchet-ring arranged on the cam-plate so as to be turned thereon by means of a pawl *p*, connected with lever *q*, so constructed and placed as to be actuated by a pin *r* on the cam-plate, and move the said ratchet-ring a distance corresponding to the length of one tooth of the said ring.

The parts thus far described are substantially the same as those shown and described in United States Letters Patent No. 413,101, granted to me October 15, 1889, and while not being a part of my present invention are referred to merely to assist in the explanation of a way in which my improvements may be applied and used.

As it is necessary when using more than one yarn on circular machines to have one of them revolve with the cam-plate, I have arranged the stud *s* upon the cam-plate *d* and placed the bobbin *t* provided with yarn for the extra yarn-carrier upon the said stud. A bracket *u* is connected with the stud *s* and supports a cross-piece *v* at its upper end, and has one end of a spring take-up *w*, provided at its free end with a yarn-guide loop or eye *x*, secured thereto as shown in Fig. 2. The free end of the cross-piece *v* is provided with a guide-eye *y*, through which the regular knitting-yarn *z* passes from its bobbin to the regular yarn-carrier *a'*, which serves the dual

purpose of a yarn-carrier and latch-opener. The yarn z passes through the slot b' in the yarn-carrier a' , and is drawn forward to the small end of the said slot by the draft of the 5 needles on the yarn, as will be readily understood by knitting artisans.

c' is a bracket secured at its rear end to the cam-plate d , which bracket extends forward and downward to a point where the needles 10 are moved out by the cams or inclines on the cam-plate to receive yarn from the yarn-guides, the forward end of the said bracket forming a support for the forward ends of the forwardly-thrust needles, and also as a 15 means for supporting the yarn-carrier a' in proper position.

d' is an upwardly-extending bracket, secured at its rear end to the bracket c' and having the upper end of the yarn-carrier e' 20 pivoted thereto. The lower end of the yarn-carrier e' is provided with a guide-eye f' , and is constructed and arranged to be moved down through the slot b' of yarn-carrier a' and through a slot g' in the bracket c' , as 25 shown by full lines in Fig. 2, or be raised up out of the said slots, as represented by dotted lines in the last-mentioned figure.

h' designates a rod provided at its outer end with an angular portion i' , adapted to 30 bear on a cam j' , formed on the ratchet-ring o . The said rod is arranged to be rocked in bearings formed in the brackets $k' l'$, and a spring m' , secured to the said rod and one of the said bearings, or it may be to the cam-plate, 35 operates with a tendency to keep the said angular portion i' pressed upon the said cam j' . At its inner end the rod h' is provided with a crank-arm n' , having a pin o' , which projects through a slot p' , formed in the yarn-carrier e' , as is clearly shown in Fig. 2.

When the knitting of regular circular work is being performed, as in the construction of the leg-and-foot portion of a stocking, but one yarn—the regular yarn z —will be fed to the 45 needles, and the yarn-carrier e' will be in the position in which it is shown by full lines in Fig. 2 and the angular portion i' of rod h' will rest upon the cam j' . When the heel or toe of the stocking is reached and the cam-50 plate is reciprocated, as is commonly done, the pin r will be raised or placed in position so as to move the ratchet-ring o a distance corresponding to the distance between one tooth and another at each reciprocation of 55 the cam-plate, which movement of the ratchet-ring will carry the cam j' from under the angular part i' of rod h' and permit the spring m' to turn the said rod, so as to cause the pin o' on the crank-arm n' and operating in the 60 slot p' to move the yarn-carrier up to the dotted-line position of Fig. 2, and so feed the thickening-yarn z' to the needles with the regular knitting-yarn z .

In the reciprocating movements of the cam-

plate the pins $q' r'$ extending up from the 65 forward end of the bracket c' will serve properly to guide the yarns to the needles.

After the knitting of a heel or toe has been completed the ratchet-ring o will have made one complete revolution, and the cam j' , coming under the bent end i' of rod h' , will operate to move the yarn-carrier e' down to the full-line position of Fig. 2, drawing the yarn z' around pin r' , through the slot s' below the needles, where it will be held down and 70 out of the way while circular knitting is to be performed by the bracket c' and be made to float from heel to toe and toe to heel without breaking or cutting the same.

It will readily be understood by reference 80 to my aforesaid patent that the ratchet-ring o may be operated automatically, and so effect an automatic operation of the entire invention.

Changes may be made in the form and arrangement of parts, as is obvious, without departing from the nature or spirit of the invention.

Having thus explained the nature of my invention, and described a way of construct- 85 ing and using the same, I declare that what I claim is—

1. The needle-bed, the needles, the cam-plate, and means connected therewith for operating the needles, combined with a bracket 90 secured at its rear end to the cam-plate and extending forward and downward to a point where the needles are moved out by the cams, said bracket being provided with the slot and pins $q' r'$, as described, the regular 100 yarn-carrier, slotted as described and supported by the forward end of said bracket, an extra yarn-carrier movable into and out of the slots in the bracket, and regular yarn-carrier to throw the yarn carried by it into 105 and out of action, and means connected with the cam-plate for moving the extra yarn-carrier, as set forth.

2. The combination, with the needles, their support, and the rotary cam-plate, of the 110 pivoted yarn-carrier e' , the movable ring on the cam-plate provided with a cam, the rod h' , connected with the pivoted yarn-carrier, and spring m , as set forth.

3. The combination, with the needles, their 115 support, and the rotary cam-plate, of the pivoted yarn-carrier e' , the movable ring o on the cam-plate, provided with a cam, the rod h' , provided at one end with an angular portion adapted to rest on ring o and to be operated by the cam thereon, said rod being provided at its opposite end with a crank-arm n' and pin o' , the latter being arranged 120 to operate in a slot formed in the yarn-carrier e' , and spring m , as set forth.

4. The combination, with the needles, their support, and the rotary cam-plate, of the bracket c' , the slotted yarn-carrier a' , secured 125

to said bracket, and the yarn-carrier e' , pivoted on said bracket and arranged to operate in the slot of yarn-carrier a' , as set forth.

5. The combination, with the needles, their support, and the rotary cam-plate, of the slotted bracket c' , provided with the pins q' r' , the slotted yarn-carrier a' , secured to said bracket, and yarn-carrier e' , pivoted on said bracket and arranged to operate in the slot 10 of yarn-carrier a' , as set forth.

In testimony whereof I have signed my name to this specification, in the presence of two subscribing witnesses, this 20th day of December, A. D. 1889.

WALTER H. STEWART.
